UNITED STATES PATENT OFFICE.

JOHN J. WANGENSTEIN AND HAROLD FEGRAEUS, OF DULUTH, MINNESOTA.

INSULATING MATERIAL.

1,379,143.

Specification of Letters Patent. Patented May 24, 1921.

No Drawing.

Application filed September 11, 1920. Serial No. 409,678.

To all whom it may concern:

Be it known that we, JOHN J. WANGENSTEIN and HAROLD FEGRAEUS, both citizens of the United States, residing at Duluth, in the county of St. Louis and State of Minnesota, have invented certain new and useful Improvements in Insulating Materials, of which the following is a specification.

This invention relates to insulating materials and has special reference to such being composed entirely of peat and moss or peat and a substance having the same general characteristics of moss.

The principal object of the invention is to produce an efficient material of this character as economically as possible and one composed of materials which are well known to be in abundance in many parts of the country.

Other objects and advantages of our invention will appear in the further description thereof.

In the process of manufacturing our improved form of insulating material the peat is preferably first thoroughly pulverized and dried either by the application of artificial heat or in the sun and the moss, which is of a more fibrous nature, though exceedingly porous, is left as nearly as possible in its natural state but is thoroughly dried. Then the moss is disintegrated and thoroughly mixed with the dried peat, when the mixture thus combined is subjected to a

mechanical pressure and made into any desired form such as thin board like pieces or 35 in the form of pipe covering, well known in the art, or, in the event of its being used in plastic form the uniting by pressure may be dispensed with and some adhesive substance mixed with the composition to act as a 40 binder for same.

Furthermore it may be found that some form of binder may be desirable for holding the peat and moss together but not add or detract from the insulating properties of 45 the combination of peat and moss.

Having thus described our invention what we claim and desire to secure by Letters Patent, is:

1. An insulating material composed wholly 50 of peat and moss.
2. An insulating material composed of pulverized, dried peat and disintegrated, dried moss.
3. An insulating material composed principally of thoroughly dried and pulverized peat having moss incorporated therein. 55

In testimony whereof we hereunto affix our signatures in the presence of two witnesses.

JOHN J. WANGENSTEIN.
HAROLD FEGRAEUS.

Witnesses:

S. GEO. STEVENS,
S. C. BRONSON.
